UNITED STATES PATENT OFFICE.

OTTO F. FOGELSTRAND, OF KENSINGTON, CONNECTICUT, ASSIGNOR TO HART MANUFACTURING COMPANY, OF SAME PLACE.

DESIGN FOR A CUPBOARD-CATCH.

Specification forming part of Design No. 5,504, dated January 30, 1872.

To all whom it may concern:

Be it known that I, OTTO F. FOGELSTRAND, of Kensington, in the county of Hartford and State of Connecticut, have invented and produced a new and original Design for a Cupboard-Catch, of which the following is a specification.

The nature of my design is fully represented in the accompanying engraving, to which reference is made.

A designates the body of the latch-case, and B the catch, each attached to their respective plates. The fronts of these are bordered by a plain ledge, *a*, and the spaces inclosed by said ledge are mainly filled in with small check-work. At each side of the central portion of the case A is an ornamental figure or elevation, *b*, having a diamond-shaped recess in its center, above and below which the said elevation assumes the form of a diamond, and at the sides it extends each way in a single shaft,

ending by a group of three leaflets. At or near the center of the parts A B there is also a raised figure, *c c*, consisting of scroll or ornamental work. The base of the knob C is large enough to cover the slot in which its shaft slides. The face of the knob C is bordered by a plain ledge, *a'*, immediately inside of which is a smaller ledge or zig-zag band, which forms a chevron. Inside of the chevron is a cluster of pointed leaves, overlapping one another and capped at the center by a small boss. The sides of the latch-case A and catch B are corrugated, as shown.

I claim as my invention—

The design for a cupboard-catch, as shown in the accompanying engraving.

OTTO F. FOGELSTRAND.
